To all whom it may concern:

In the drawing:

Fig. 1 is a top view of one of my new decorative automobile hood trims;

Fig. 2 is a side view of the hood trim;

Fig. 3 is a front view of one of the trims; and
Fig. 4 is a perspective view showing the pair
of the hood trims as they appear when in use.

The characteristic features of the present design reside in the decorative hood trim plates which are adapted to be attached in pairs to the front portions of the hood covers of an automobile.

I claim:

The ornamental design for a decorative automobile hood trim, substantially as shown and described.
